UNITED STATES PATENT OFFICE.

WALTER W. HODGSON, OF PHILADELPHIA, PENNSYLVANIA, ASSIGNOR TO WALTER W. HODGSON, INC., OF PHILADELPHIA, PENNSYLVANIA, A CORPORATION OF PENNSYLVANIA.

SELECTING MACHINE FOR DICTATING THE PUNCHING OF HOLES IN JACQUARD CARDS.

Application filed February 24, 1927. Serial No. 170,461.

My invention relates to machines for punching jacquard cards used to produce designs in woven fabric. Jacquard cards are old and well known in the art, and it is well understood that the holes in the cards dictate the raising of the heddles in the loom to produce a certain weave and pattern.

To correctly locate and punch the holes in jacquard cards is a highly skilled art and has heretofore been done by hand, and that only by highly skilled operators.

It is the object of my invention so to simplify this operation that jacquard cards may be punched quite readily without the requirement of highly skilled labor. To this end, I have devised a duplex selecting mechanism to be used in connection with the regular jacquard card punching machine, known in the trade as a repeater, whereby master cards of simple punching, used in my new machine, dictate which punches shall be active to produce the desired weaves.

My invention is a duplex selecting mechanism having two selecting cylinders, two series of needles, two series of hooks, and two griffe frames operating simultaneously, controlling one series of slideable rods or locking bolts of the punching machine. I divide the process into two distinct steps, though operating simultaneously, first dictating the punching for the pattern, and the second the punching for the weave. To this end, my invention comprises a cylinder over which is adapted to pass a series of cards or continuous strip of paper perforated to unlock punches to produce the desired pattern, without regard to the weave. Back of this

I provide another cylinder over which a series of master cards is adapted to pass, these cards being perforated to unlock punches to produce correct punching of the jacquard cards for the kind of weave desired. The weave cylinder is the determining factor, i. e.: the pattern cylinder may lock the punches to make the pattern, the weave cylinder will unlock some of these to put the proper weave in the pattern.

Above the punches are rods or locks normally holding the punches operative to punch holes in the jacquard cards. When any of these rods are retracted their punches become inoperative, and holes are not formed

in the jacquard cards. A series of horizontal hooks arranged above the before mentioned cylinders are connected to the ends 55 of these rods, long hooks reaching over the pattern cylinder and short hooks over the weave or master card cylinder. They are so arranged that a long hook and a short hook are connected to the end of each rod, so that 60 any punch may be rendered inactive by its lock or rod being retracted by a pull upon either the long or short hook connected with it.

The hooks all pass through slotted plates 65 or grids which are pulled out regularly with every operation of the punching mechanism, so that all the hooks would be pulled out at every operation if they were all allowed to remain in operative relation with 70 the slotted plate or grid. To render certain hooks inoperative, a series of vertical needles is arranged in connection with each series of hooks whereby hooks may be raised to an inactive position, and these needles are 75 moved to dictate the action of the punches by means of the before mentioned cylinders with the perforated paper strip and the master cards.

In order that the operation may be more 80 fully followed and understood, I append the following detailed description of my invention, in connection with the accompanying drawings, in which:

Fig. 1, is a diagrammatic sectional elevation through the apparatus in connection with a jacquard card punching machine.

Fig. 2, is a partial section taken on line 2—2 of Fig. 1.

Fig. 3, shows a portion of a jacquard card.

Fig. 4, is a perspective view showing several long hooks with their connections.

Fig. 5, is a face view of a portion of the slotted or griffe plate.

Fig. 6, is a perspective view showing several short hooks with their connections.

Fig. 7, is a section through one side of the machine showing means for operating the cylinders; and

Fig. 8, is an end view of same partly in 100 section.

For the purpose of illustrating my invention I have shown in the accompanying drawings one form thereof which is at pres-

ent preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to Fig. 1, the punching machine comprises punches 10 slidable vertically in the machine frame. Below the punches a perforated table 11 is arranged to carry the jacquard cards 12 to be punched and is operable vertically with respect to the punches by means of cams on a shaft 13 which is a regularly driven shaft in the machine. Only one row of ten punches is shown in the drawing, but it is understood that there are any number of these rows across the front of the machine, according to the length and width of the jacquard card and the spacing of the perforations.

Above each punch is its lock, the projecting end of a slidable rod 14, which is normally held in locking position by springs 15. That is, the ends of rods 14 that project above punches 10 lock those punches against vertical movement, so that they will perforate the jacquard card when it is raised against them in the operation of table 11. To the rear end of each rod 14 are two wire connections, one 16 connected with a long hook 18 and 17 connected with a short hook 19.

As shown clearly in Figs. 1, 2, and 5, both the long and short hooks pass through a grid consisting of vertical bars 20 and horizontal bars 21 upon which latter the hooks rest and are bent to restrain them from the forward pull exerted by springs 15. Only one vertical row of these hooks is shown in Fig. 1, but as seen by Fig. 2 there are supposed to be as many rows in width as there are rows of punches required in the length of the card to be punched.

The long hooks 18 extend through to the rear of what I call my selecting machine where they pass through a guide plate 22 and griffe frame 23 beyond which their ends are doubled back to form heads 18^a. Guide plate 22 is fixed to the machine frame 24 and is provided with vertical slots 25, Fig. 4, through each of which passes one of the long hooks 18. Griffe frame 23 has similar vertical slots 26, one for each long hook. These slots are too narrow to allow the passage of the hook heads 18^a therethrough but they have horizontally aligned enlargements 26^a through which the hook ends may freely pass.

The griffe plate is slidably mounted on frame 24, as will be hereinafter described, and when it is moved forward from its normal position, Figs. 1 and 4, it will pull all

the hooks 18 whose heads 18^a are not on a level to pass through enlargements 26^a, Fig. 5. Normally, I prefer to have hooks 18 lie in slots 26 below the level, but they may be in other positions, and a movement of the griffe plate forward, Figs. 1 and 4, would pull all the long hooks and unlock all of the punches in the punching machine. There is a group of vertical needles 27 arranged beside hooks 18 and each needle has an offset 75 27^a, which embraces one of said hooks, so that by raising a needle, as the one marked in Fig. 4, its hook may be raised to bring its head in line with enlargement 26^a of its slot, as shown marked *n* in Fig. 4. In its regular movement forward, all the hooks that have been so raised by their needles will remain unaffected and allow the punches connected with them to perforate the jacquard card, but all the hooks that have not 85 been so raised will unlock their punches.

Needles 27 are suspended in the machine as at 28, Fig. 1, and pass downward, one beside each hook, in regular formation, passing slidably through a perforated guide 90 plate 29, and directly beneath them is arranged a cylinder 30, which is vertically movable against the needle ends. In the drawings cylinder 30 is shown as of four sided form, presenting a flat face to the needle ends, said face being perforated in alignment with the needles, so in an upward movement of the cylinder, the needle ends will all enter holes and not be operated.

A paper strip or series of cards represented at *p*, Fig. 1, is adapted to be passed over cylinder 30, and has perforations corresponding with certain of the perforations in said cylinder, forming a pattern, by which means certain needles may be prevented from entering the holes in the cylinder and be moved upward, carrying their hooks, and certain other needles passing through perforations in the paper strip will not be affected.

Paper strip *p* may be perforated by machine or by hand in a simple manner, without regard to the form of weave desired, but merely dictating the pattern or color scheme of the design intended for the jacquard 105 cards.

I have arranged that the short hooks 19, each connected to a punch lock as are the long hooks, shall separately dictate the form of weave desired. To this end the short hooks are hooked at their rear ends as at 19^a and pass through a griffe frame which consists of thin plate bars 40 arranged vertically between the vertical rows of hooks. The long hooks pass freely between these bars and are unaffected in any way, but the hooked ends 19^a of the short hooks are arranged normally to catch over the edges of the bars, so that when this griffe frame is moved forward, see Fig. 1, it will pull all 115 120 125 130 135

such short hooks and unlock their punches. Above this normal position of each short hook, a slot 40^a is provided in the griffe bar 40, of sufficient depth to allow a hook to be unaffected by the movement of the griffe bars, when it is raised so that its hooked end 19^a aligns with its slot as indicated at *o* in Fig. 6. In order to thus raise certain short hooks to inactive position, I provide 10 another series of vertical needles 41, having offsets 41^a, Fig. 1, embracing the short hooks, in exactly the same manner as needles 27 embraced the long hooks. Needles 41 are similarly mounted to needles 27, and directly 15 beneath them is arranged a cylinder 42, which may be similar in every way and similarly mounted to cylinder 30.

A series of master cards, represented at *r*, Fig. 1, is arranged to pass over cylinder 42, 20 and the perforations of these master cards cause certain needles 41 to act to dictate the punching of holes in the jacquard card, just as did the perforated strip *p* on cylinder 30. These master cards may be perforated 25 by machine or by hand, in a simple manner, without regard to the pattern or color scheme desired, but merely dictating the form of weave as satin, twill, or the like. The result is that certain holes in the jacquard 30 card, as *x*—*x* Fig. 3, are dictated by the paper strip on cylinder 30 and determine the raising of heddles in the loom in accordance with the pattern, and the intermediate holes *y* are dictated by the master cards on cylinder 42 and determine the movement of heddles in the loom, four to one or seven to one, or any combination, to produce a desired 35 form of weave.

Griffe frames 23 and 40 are moved back 40 and forth at regular intervals synchronously with movements of the punching machine. For instance, as shown in Fig. 1, the griffe frames may be connected together by a yoke 43 pivotally connected with a rod arm 44. 45 The rod arm may be connected by rod 45, bell crank 46, and link 47 with a lever 48, adapted to be moved by the moving punch table.

Cylinders 30 and 42 may be moved up and 50 down and given step by step quarter turn by the following means, referring to Figs. 7 and 8.

The shafts of these cylinders are mounted in bearings in a common frame 50 at each 55 side of the selecting machine frame 24, and carry at one end star wheels 51, actuated by wheels 52, which receive motion from vertical shafts 53 by means of miter gears 54. As these parts are all carried by frames 50, 60 and are adapted to be raised and lowered, shafts 53 have slot and pin connected ends 55 mounted in the fixed frame 24 and driven by miter gears from a shaft 56 which extends rearwardly from the punching machine, and 65 which is rotated in time with the punching

machine, by means not shown, as it forms no part of my invention.

Miter gears 57, also on shaft 56, through the equal gears 58 drive a cam shaft 59, which carries on each end cams 60. These 70 cams are adapted to raise and lower rods 61, mounted to slide vertically in brackets on the machine frame, and to which frames 50 are connected on both sides of the machine.

Prior to starting the machine, a linked 75 series of master cards are hung on cylinder 42 and the perforated paper strip is placed on cylinder 30, both being provided with margin holes for engagement with pins *x*, Fig. 8, at the ends of the cylinders for the 80 purpose of alignment.

The machine is then started, and cams 60 raise frames 50 carrying both cylinders against the lower ends of the two series of 85 needles 27 and 41. The needles that pass through holes are not moved upward and the hooks which they embrace are pulled by the movement of frame 43 so that the locks of their punches are retracted and holes are 90 not punched. Similarly the needles that are raised by striking imperforate portions of the master card or paper strip, raise their hooks to the level where they are unaffected by movement of griffe frames 23 and 40, and their punches remain locked and therefore 95 punch holes in the jacquard card which has been placed on table 11 in the punching machine. As the hooks are arranged in pairs, one long one and one short one controlling each punch lock, it is only necessary for one of them to be pulled to unlock 100 a punch. A long hook may be raised to position 22, Fig. 4, by cylinder 30, and do no pulling, but its shorter mate, which may be 105 *t*, Fig. 6, remaining unraised by cylinder 42, will be pulled by griffe frame 40 to retract the locking rod which is connected with this pair of hooks.

What I claim is:

1. In apparatus of the character stated, 110 the combination with a jacquard card punching machine of a selecting mechanism operatively connected with respect to said jacquard card punching machine, said selecting mechanism being provided with two selecting cylinders.

2. In apparatus of the character stated, 120 the combination with a jacquard card punching machine of a selecting machine operatively connected with respect to said jacquard card punching machine, said selecting machine being provided with two selecting cylinders, two series of needles, two series of hooks.

3. In apparatus of the character stated, 125 the combination with a jacquard card punching machine, a selecting machine operatively connected thereto, said selecting machine being provided with two selecting cylinders, needles operated therewith, said needles 130

controlling hooks, the hooks operated by two griffe frames, hooks connected to stoppers covering or locking punches.

4. In apparatus of the character stated, 5 having two cylinders, one cylinder operating a series of needles which control a series of hooks operated by a horizontal griffe frame, another cylinder operating a series of needles which control a series of hooks operated by a perpendicular griffe frame, one hook of each series connected to each stopper.

5. In selecting machine of the character stated, in combination with a jacquard card 15 punching machine in which are combined two cylinders, two series of needles, two series of hooks and two griffe frames, so combined, constructed and connected to operate one series of slidable rods, said slidable rods locking or unlocking punches.

6. In apparatus of the character stated the combination with a jacquard card punching machine of a selecting machine operatively connected with respect to said jacquard card punching machine, said selecting machine being provided with two selecting cylinders for needles.

7. In apparatus of the character stated 30 the combination with a jacquard card punching machine of a selecting machine operatively connected with respect to said jacquard card punching machine, said selecting machine being provided with two selecting cylinders for needles, of which the needles of one cylinder control the hooks of a horizontal griffe-frame.

8. In apparatus of the character stated

the combination with a jacquard card punching machine of a selecting machine operatively connected with respect to said jacquard card punching machine, said selecting machine being provided with two selecting cylinders for needles, of which the needles of one cylinder control the hooks of a horizontal griffe frame and of which the needles of the other cylinder control the hooks of a perpendicular griffe frame.

9. In apparatus of the character stated the combination with a jacquard card punching machine, the punches of which are controlled by stoppers, of a selecting machine operatively connected with respect to said jacquard card punching machine, said selecting machine being provided with two selecting cylinders for needles, of which the needles of one cylinder control the hooks of a horizontal griffe frame and the needles of the other cylinder control the hooks of a perpendicular griffe frame.

10. In apparatus of the character stated 60 the combination with a jacquard card punching machine the punching of which is controlled by stoppers, of a selecting machine having a duplex selecting mechanism operatively connected with respect to said jacquard card punching machine, said selecting machine being provided with two selecting cylinders for needles of which the needles of one cylinder control the hooks of a horizontal griffe frame and of which the needles of the other cylinder control the hooks of a 65 perpendicular griffe frame.

WALTER W. HODGSON.
